UNITED STATES PATENT OFFICE

96,894

DESIGN FOR A COLLAR CLASP OR SIMILAR ARTICLE

Joseph Blaser, New York, N. Y.

Application July 18, 1935, Serial No. 57,716

Term of patent 3½ years

To all whom it may concern:

Be it known that I, Joseph Blaser, a citizen of Colombia, S. A., residing at New York, in the county of New York, and State of New York, have invented a new, original, and ornamental Design for a Collar Clasp or Similar Article, of which the following is a specification, reference being had to the accompanying drawing, forming part thereof.

I claim:—

The ornamental design for a collar clasp or similar article as shown.

JOSEPH BLASER.
